UNITED STATES PATENT OFFICE.

WALTER J. CATTIN, OF OMAHA, NEBRASKA.

VALVE TOOL.

Application filed December 27, 1921. Serial No. 524,927.

To all whom it may concern:

Be it known that I, WALTER J. CATTIN, a citizen of the United States, residing at Omaha, in the county of Douglas and State 5 of Nebraska, have invented certain new and useful Improvements in Valve Tools, of which the following is a specification.

The present invention relates to valve or operating tools, and more particularly to a 10 tool or key for use in turning off the valve located below the surface level of the ground to control the flow of water, gas and the like to buildings.

An object of the present invention is to 15 provide a tool or key of this character which is relatively small and may be conveniently carried by plumbers and the like without the necessity of carrying about a relatively long, heavy and cumbersome device as is the case 20 at the present time.

Another object of the invention is to provide a key and cooperating joint sections which may be used in conjunction with 25 scrap gas or water pipe for building up, temporarily, a key or tool, and which obviates the necessity of transporting the entire length of a tool, and which permits of the collapsing or folding of the tool into a relatively small space when it is necessary to 30 carry the entire device.

A further object of the invention is to provide a tool of this character which is provided with a plurality of joints adapted to be arranged for permitting a flexible or universal movement of the tool shank or handle, 35 so that the tool may be used in confined places, and where a straight shank or handle cannot be conveniently manipulated.

With the foregoing and other objects in 40 view, the invention will be more fully described hereinafter, and will be more particularly pointed out in the claims appended hereto.

In the drawings wherein like symbols refer 45 to like or corresponding parts throughout the several views,

Fig. 1 is a side elevation, partly broken away, of a tool or key constructed according to the present invention, and showing the 50 upper portion thereof swung at an angle to the general axis of the tool.

Fig. 2 is a side elevation of the same in a folded or collapsed position.

Fig. 3 is an edge view of one of the angles 55 or hinged joints of the tool.

Fig. 4 is a longitudinal section through the

head portion of the tool, showing the shank and locking key therein.

Fig. 5 is a transverse section through the same, taken substantially on the line 5—5 60 of Fig. 4.

Fig. 6 is a fragmentary side elevation of the upper section of the tool showing one form of handhold therefor.

Fig. 7 is a side elevation of a modified form 65 of handhold for the upper section of the tool.

Referring to the drawing 10 designates the head of the tool which is preferably of cylindrical form, having a downwardly or outwardly flaring key slot, or kerf 11, into which 70 is adapted to seat the T-head of a valve, such as a valve which controls a water or gas main.

The head 10 is provided with a shank 12, which projects inwardly from the head, and 75 which is adapted to fit in the end of a pipe section 13. The pipe section 13 may be ends of pipe sections 13, and the keys 19 are adapted to lock the shanks in the pipe sections to form rigid parts thereof. One shank 80 such as the shank 17, carries a socket member 20 which may be of U-shape with its axis at right angles to that of the shanks 17, and which is adapted to receive a tongue 21 carried upon the opposite shank 18. The tongue 85 21 is relatively narrow, and is adapted to fit in the socket 20, and is turned substantially at right angles to the axis of its shank 18, and lies between the spaced portions of the socket 20. A hinge pin 22 is secured through 90 the socket 20 and the tongue 21 at the free end portions of the socket and tongue so as to pivotally connect the same in offset relation to the longitudinal axis of the joint. In this manner, the sections may swing one 95 upon the other, with the pivot 22 as an axis as shown at the top of Fig. 1. The socket 20 may also seat against shoulders 23 which are formed at opposite sides of the tongue 21, and which are adapted to hold the pipe sections and joints normally in alignment.

By offsetting the pivots 22 of the joints, the latter permitting the pipe sections 13 to be folded one upon the other into substantially parallel relation so as to materially 105 shorten the length of the tool when the latter is folded, so that the tool may be placed in a hand bag, tool box or the like.

When the tool is applied to a valve the same may be rotated by use of a pipe wrench 110 or the like applied to the upper section of the tool, or the upper section 13 of the tool

may be turned over at right angles at its upper extremity to form a handhold 13^a as shown in Fig. 6. Another form of permanent handhold is shown in Fig. 7 where a flat loop 13^b is provided with a socket flange 13^c adapted to fit over the upper end of the section 13 and be riveted or otherwise permanently secured thereto. These handholds, 13^a and 13^b are adapted to facilitate the turning and lifting of the length of scrap iron pipe or the like, generally used in the construction of water and gas supply pipes, and which may be found where building operations are carried on. The shank 12 is provided in one side with a longitudinal slot or keyway 14 in which is fitted a key or spline 15, and the latter is of substantially triangular cross section, with one side seat against the bottom of the groove 14, and the adjacent edges forming a dove tail tongue, adapted to fit in underlying relation against the lateral overhanging edges of the slot 14. The key 15 therefore is held to the shank 12 and presents an outwardly projecting sharp edge 16, arranged to bite into the inner wall of the pipe section 13. This head 10 with its shank may therefore be used as a key member and carried by a plumber to the valve, and may be fitted in a length of scrap pipe which may be found at the location of the valve. The head 10 is forced against the end of the pipe with the shank 12 projecting into the hollow of the pipe. The key 15 may be tapered, as shown in Fig. 4 so as to adapt the key member to pipe sections 13, of different internal diameters, and also for the purpose of more readily affecting the biting of the key 15, into the end and inner wall of the pipe section.

Where the valve is located at a considerable depth below the surface level of the ground it may be desirable to use a number of pipe sections 13, and it may also be found more convenient to utilize a plurality of short pipe sections than in attempting to find a single pipe section of sufficient length. To meet these conditions, the invention provides a hinge or knuckle which is in the form of a pair of shanks 17 and 18 of a construction similar to the shank 12 of the head, and which are provided in like manner with locking keys 19. The shanks 17 and 18 are adapted to be fitted in adjacent tool and may be used in connection with a pipe or other wrench if found convenient.

In assembling the joints or knuckles of

the tool, as shown in Fig. 1, the pivots 22 are preferably located at opposite sides of the tool, so that a universal joint is provided by each adjacent pair of the hinges, and also so that the sections 13 may be folded back and forth one upon the other as shown in Fig. 2.

After the tool has been used, the plumber or workman may readily remove the head 10 and the hinge joints from the pipe sections 13, and discard the latter so that it will not be necessary to carry about the heavy and cumbersome sections 13.

I do not wish to be restricted to the size, form, and proportions of the various parts, and obviously changes could be made in the construction herein described without departing from the spirit of the invention, it being only necessary that such changes fall within the scope of the appended claims.

What is claimed is:

1. A valve operating tool for use with scrap pipe, comprising a head section for engagement with the valve, and provided with a shank adapted to fit in the end of a length of pipe, a spline dove-tailed in the side of the shank, and having a cutting edge projecting beyond the side of the shank, said shank being adapted to be fitted in the end of a length of pipe, and said spline being adapted to bite into the inner wall of the pipe for locking the shank therein, and a plurality of independent hinge sections adapted to be fitted between the adjacent ends of a plurality of lengths of scrap pipe for building up a tool of the desired length.

2. A valve operating tool for use with scrap pipe, comprising a head section arranged to fit upon a valve for turning the same, and having a shank adapted for insertion in the end of a length of scrap pipe, said shank having in one side a longitudinally extending dove-tail groove, and a triangularly shaped spline seated in said dove-tail groove, and having an edge portion exposed beyond the side of the shank for biting engagement in the inner wall of the pipe section, said spline being tapered at said connecting edge for accommodating the shank to pipe sections of various diameters and for wedging the spline into place.

In testimony whereof, I have affixed my signature in presence of two witnesses.

WALTER J. CATTIN.
